F. H. FIELD

ICE RUG

Filed Sept. 26, 1927

Inventor
Frank H. Field

By Clarence Walker

His Attorney

UNITED STATES PATENT OFFICE.

FRANK H. FIELD, OF JAMESTOWN, NEW YORK.

ICE BUG.

Application filed September 26, 1927. Serial No. 221,905.

This invention relates to an improvement in ice rugs and more particularly to one adapted to be used in vending ice.

In its preferred embodiment this invention is a type of rug or protector to be carried upon the shoulder of a person vending ice, whereby such person is protected from the cold and wet while carrying the ice.

A further use to which it is put is for the ice vender to spread the rug before an ice box to prevent the loose or chipped pieces of ice from being dropped and left upon the floor where they will melt and cause considerable inconvenience to the purchaser of the ice.

To fully explain the advantages of this invention, it is necessary to refer briefly to the present day practice of protecting or failing to protect an ice vender. When the vender leaves his wagon with a piece of ice upon his shoulder he at best has scant protection from the wet of the melting ice, or from the sharp edges thereof. When the vender reaches the ice box it is invariably necessary for him to lay the cake of ice upon the floor, open the door of the ice compartment, and remove all food stuffs and small pieces of ice. The fresh piece of ice is then placed within the compartment and, as is often the case, there is scant room for the small piece or pieces of ice which were previously within the compartment. These pieces must be chipped or broken up in order to be placed therein and when the work of filling the ice box is completed, many such pieces of ice remain upon the floor and melt causing a great deal of wet and inconvenience.

It is applicant's endeavor to provide an ice rug which may be used to protect the vender of ice from an inhuman daily wetting and also to prevent an unnecessary accumulation of ice chips and water when an ice box is being filled.

An object of this invention is to provide an ice rug which, being placed upon the vender's shoulder, will catch all the water dripping from the ice and protect him therefrom.

Another object of this invention is to provide an ice rug which, being laid before an ice box, will receive all the chips of ice incident to filling the ice box in order that they may be readily removed.

Other objects of this invention will appear

from a consideration of the following specification taken in connection with the accompanying drawings and in which

Fig. 1 is a general view of one form of this invention in use upon the shoulder of an ice vender;

Fig. 2 is an enlarged plan view of the ice rug;

Fig. 3 is a fragmentary view of the base of the rug showing a slight modification in forming the trough;

Fig. 4 is a sectional view taken on the line 4—4 of Fig. 2, illustrating the manner of securing the rails to the rug; and

Fig. 5 is a sectional view taken on the line 5—5 of Fig. 2, illustrating the manner of securing the trough to the rug.

Referring to the drawing and more particularly to Fig. 2 this invention is generally indicated by the reference numeral 10 and comprises a body portion 11, rails 12, and trough 13. The body portion 11 is made of any strong water proof material such as canvas. In its preferred form the material used is heavy canvas being thoroughly water proofed.

The rails 12 are formed by a seam or binding portion 14 turned over a flexible material 15. The material 15 may be made of any flexible material such as rubber, rope, etc., and in the present embodiment is shown as rope. The rope 15 is secured at one end to the rug adjacent one end of the trough 13 and extends continuously around said rug to the other side of the trough. The looped portion 16 of the rope 15 is free and clear of the body of the rug 11, said rug being cut away at this point. By means of the loop 16 the rug may be grasped and held upon the shoulder of the ice vender or may be hung up thereby when not in use. A double row of stitching 18 along the seam 14 secures the rope 15 within said seam and prevents it from possible withdrawal from the body 11 of the rug. The lower end of the rug 19 is secured to the inner face of the trough 13 and forms a lining therefor as is clearly shown in Fig. 5 of the drawing.

The trough 13 comprises a metal strip substantially U shaped, the front edge of which terminates in an inwardly turned flange 20.

As is shown in Fig. 2, the trough 13 is slightly narrower in width than the rug 10

and is adapted to engage and be secured to the body portion 11 of the rug between the rails 12 by means of rivets 22 which pass through both front and rear walls of the trough and the end 19 of the rug. Inasmuch as the body of the rug completely lines the trough 13, being secured thereto along its sides by rivets 22 and at its end 21 by means of the flange 20, there is no possibility of water escaping therefrom.

In order to facilitate the positioning of this rug upon the shoulder of a vender, a leather strap 24 is secured thereto by rivets 25 upon the underface of the body portion 11. By means of this strap, the rug may be carried upon the shoulder without grasping it and holding it by the loop 16.

In Fig. 3 is shown a slight modification of the manner of securing the trough 13 to the body 11 of the rug. In this instance the trough 13 is positioned upon and over the end of the rug in a similar manner to that shown in Fig. 2. However, a further strip 26 of the material used in the rug incases the metal trough 13 and holds it in position by means of the stitching 27 which continues completely around said edges of the trough. In this showing the trough not only has a lining of water proof material but also has an outside cover therefor. The only difference between this construction and that shown in Fig. 2 is that in this embodiment the metal trough 13 is enclosed and secured solely by means of the stitching whereas in Fig. 2 rivets secure the trough to the body 11 of the rug.

When in use this rug is slung over the shoulder of the ice vender and is adapted to receive a cake of ice thereon. As the ice melts the water therefrom runs down the body portion 11 of the rug between the rails 12 thence into the trough 13. The vender is entirely protected from the wet and cold of the ice at all times due to the use of the rug. As he carries the ice into a building the drippings of water therefrom will not be scattered promiscuously in a sort of trail from the door of the building to the door of the ice box due to the fact that the trough catches and retains all such water.

When the vender has reached the ice box he removes the cake of ice from his shoulder and lays the rug down upon the floor in front of the ice box and places the cake of ice thereon. He now has both hands free to open the ice box, remove all food and pieces of ice from within and may place the cake of ice within the compartment. It is usually at this point in the process of filling an ice box that the general muss of ice box filling occurs. A large cake of ice has been placed in the compartment. As a rule, he has no choice but to do this chipping on the floor but with the use of the ice rug chipping and breaking up of the ice may be done without the necessity of any muss whatsoever, since the chips of ice

and the water dripping therefrom are upon the ice rug. The process of filling the compartment having been completed, the ice vender may grasp the rug by the loop or handle portion 16 and all the chips and water will run down the face of the rug into the trough 13. The rug may then be carried out of the building leaving no disorder in front of the ice box nor on the way out, and may be emptied out of doors at the will of the vender.

While only one form of this invention has been shown and described, applicant does not intend to be limited thereto since it is obvious that other modifications and adaptations may be made without departing from the spirit and scope of this invention as set forth in the following claims.

Having thus set forth my invention what I claim as new and for which I desire protection by Letters Patent is:

1. An ice rug comprising a body portion, rails formed from a flexible material enclosed within the seams of said body portion, the upper end of said rail forming a loop by which to grasp said rug and a trough formed along the lower edge of said rug, said trough being formed by doubling back upon itself the lower end of said body portion and a metal strip formed to engage said trough and having means by which to seal the vertical edges of said body portion and said metal strip whereby said trough may receive and retain water caused by the melting of a cake of ice.

2. An ice rug comprising a body portion, seams terminating the longitudinal edges of said body portion, rails formed from a flexible material encased within the seams of said body portion, the upper end of said flexible material extending beyond the upper end of said body portion forming a loop by which to grasp said rug and a trough terminating the lower edge of said rug, said trough being formed by doubling back upon itself the lower end of said body portion, the edges of said trough being united with said body portion whereby said trough may receive and retain water caused by the melting of a cake of ice.

3. An ice rug comprising a body portion, seams terminating the longitudinal edges of said body portion, rails formed from a flexible material encased within the seams of said body portion, the upper end of said flexible material extending beyond the upper end of said body portion forming a loop by which to grasp said rug and a trough terminating the lower edge of said rug, said trough being formed by doubling back upon itself the lower end of said body portion, the edges of said trough being united with said body portion and means retaining said trough in a position such that water caused by melting ice may flow downwardly upon said body portion and into said trough, said means

being adapted to prevent inadvertent collapsing of said trough when containing water.

4. An ice rug comprising a body portion, a U shaped metal trough, closed at its vertical ends, terminating the end of said body portion and being aligned thereby, and rails encased within the seams of the vertical edges

of said body portion, said rails extending from below the edge of said trough upwardly 10 beyond the upper end of said body portion and forming a loop by which to grasp said rug.

In testimony whereof I have affixed my signature.

FRANK H. FIELD.
